UNITED STATES PATENT OFFICE

2,419,494

PRESSER DEVICE FOR SEWING MACHINES

Nicholaus Knaus, Cranford, N. J., assignor to The Singer Manufacturing Company, Elizabeth, N. J., a corporation of New Jersey

Application October 12, 1945, Serial No. 621,993

10 Claims. (Cl. 112—235)

1

This invention relates to presser devices for sewing machines and more particularly to presser devices for overedge sewing machines of the type disclosed in my United States Patent No. 2,238,796, Apr. 15, 1941.

In sewing machines of that type, the presser-foot is carried by the forward end of a horizontally disposed spring-depressed presser-bar. This bar is so connected, at its rear end, to the sewing machine frame that the bar and the presser-foot carried thereby may be moved vertically in their operative position, to permit introduction or adjustment of the work beneath the presser-foot, or swung out laterally to an inoperative position, as for example, to give access to the needle and loopers for the purpose of threading those elements. Manually releasable means is commonly provided for locking the presser-bar in its operative position.

This invention has as an object to provide improved treadle-controlled means for lifting the presser-bar and the presser-foot carried thereby.

Another object of the invention is to provide improved means for applying the spring pressure to the presser-bar and for releasably locking the bar in its operative position.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is an end elevation of an overedge sewing machine embodying the present invention.

Fig. 2 is a plan view of the left end portion of the machine shown in Fig. 1, with a part of the machine frame in section.

Fig. 3 is a rear view of a portion of the machine and of the presser device and its treadle-actuated lifting mechanism.

Fig. 4 is a sectional view taken substantially on the line 4—4 of Fig. 2.

Fig. 5 is a sectional view taken substantially on the line 5—5 of Fig. 3, showing a presser-bar locking device, later to be described, in released position.

Fig. 6 is a detail sectional view taken substantially on the line 6—6 of Fig. 1.

Referring more specifically to the drawings, the invention is disclosed as embodied in an overedge sewing machine comprising a frame 1 which

2

carries a work support 2, a throat-plate 3, and a conventional work-feeding mechanism including a four-motioned feed-dog 4, operating through slots in the throat plate. The machine also includes overedge stitch forming mechanism comprising a reciprocating thread-carrying needle 5, and under or needle-loop-taking looper 6 and an overedge looper 7 which cooperates with the needle 5 and the looper 6 in the formation of overedge stitches.

The machine further includes a presser-device which forms the subject of the present invention. This presser-device comprises a horizontally disposed presser-bar 8 carrying, at its forward end, a presser-foot 9 which normally overlies the feed-dog 4 and cooperates therewith in the feeding of the work. At its rear end, the presser-bar is connected to the machine frame by a universal joint thus permitting the presser-bar, and the presser-foot carried thereby, to be moved vertically to permit introduction of the work beneath the presser-foot and also to be swung out laterally into an inoperative position, as indicated in dotted lines in Fig. 2, to give access to the needle and loopers for the purpose of threading those elements.

The universal joint, by means of which the presser-bar is connected to the frame, comprises a U-shaped yoke 10, journaled on a horizontal stud 11 secured in the frame 1 by set screws 12, and having a laterally offset ear 13 to which the bifurcated rear end 3a of the presser-bar is journaled on a vertically disposed pivot screw 14. By means of this universal mounting, the presser-bar is adapted to be moved vertically and horizontally, as above described.

The presser-bar and the presser-foot carried thereby are urged downwardly by a spring-pressed plunger 15 supported, for endwise movement, in a thimble 16 threaded into a bore 16a provided by a tubular portion 17 of the frame 1. At its lower end, the plunger 15 is formed with a head 18, fitted between spaced ears 17a provided at the lower end of the frame-portion 17, and which head straddles and bears upon the presser-bar 8. The head 18 carries a cylindrical stud 19 adapted to be seated in a notch 20 formed in the upper edge of the presser-bar 8. The plunger 15 is pressed downwardly, to cause the stud 19 to bear in the notch 20, by a coil spring 21 surrounding the plunger and bearing at its upper end against the thimble 16 and at its lower end on the head 18.

Finger-actuated means is provided for moving the plunger upwardly, in opposition to the spring

21, to the position shown in Fig. 5; thereby to lift the stud from the notch 20 and to free the side walls 18^a of the head 18 from the presser-bar 8, to permit the bar to be swung laterally as indicated in dotted lines in Fig. 2. This means comprises a lever 22 fulcrumed on a shoulder screw 23 threaded into the outer one of the ears 17^a. The lever 22 is provided with an aperture 24 through which extends a finger 18^b projecting rearwardly from the head 18 (Fig. 5). Thus clockwise movement of the lever 22, as seen in Figs. 1 and 5, causes the lower wall of the aperture 24 to act against the finger 18^b and to raise the plunger 15 in opposition to the spring 21 for freeing the stud 19 and the head 18 from the presser-bar 8, as above described. When the finger lever 22 is released, the spring 21 again forces the plunger downwardly. With the presser-bar thrown out to its inoperative position, the downward movement of the plunger 15 causes the finger 18^b to bear upon the lower wall of the aperture 24 thus turning the lever 22 counterclockwise (as viewed in Fig. 1) about the screw 23. This movement of the lever 22 causes a stop 25, provided by the lever, to be brought into contact with an abutment shoulder 17^x provided by the outer ear 17^a of the frame portion 17, thereby stopping the turning movement of the lever 22 and consequently limiting the downward movement of the plunger 15.

Improved treadle-actuated means also is provided for raising the presser-bar, in opposition to the spring 21, to permit introduction or adjustment of the work beneath the presser-foot. This means comprises a rod 26 journaled in a portion of the machine frame 1 parallel to the presser-bar 8 and carrying, at its rear end, a laterally projecting arm 27 adapted to be connected, by a chain 28 or other suitable connection, with a conventional knee or foot actuated treadle, not shown. Adjacent its forward end the rod 26 has secured to it, by set screws 29, a collar 30 having an offset arm 31 providing a portion 32 underlying a laterally projecting portion 33 of the presser-bar. Preferably, but not necessarily, the portion 32 of the arm 31 is formed as a roller stud and the laterally projecting portion of the presser-bar comprises a shouldered stud having a shank 34 extending through an aperture 35 in the presser-bar and secured thereto by a nut 36.

The rod 26 is normally biased counterclockwise, as seen in Figs. 2 and 4, to a position in which a shoulder 31^a of the arm 31 abuts a portion of the frame 1 as shown in Fig. 4, thereby affording a clearance between the arm 31 and the overlying portion 33 of the presser-bar. This clearance permits the presser-foot and the presser-bar to rise and fall, under the action of the feed-dog, without the presser-bar contacting the lifting arm 31. This biasing of the rod 26 is effected by a coil spring 37 surrounding the rod and having one end 37^a fitted into an aperture in the arm 27. The opposite end 37^b of the spring 37 projects through a slot 38 in a portion of the frame 1.

From the foregoing it will be apparent that this invention has provided improved means for holding the presser-bar in its operative position; for releasing the presser-bar and permitting it to be swung outwardly to an inoperative position; and for lifting the presser-bar and the presser-foot carried thereby, to permit introduction and manipulation of the work beneath the presser-foot.

Having thus set forth the nature of the invention, what I claim herein is:

1. In a sewing machine having a horizontally disposed presser-bar pivoted on a horizontal axis, a presser-foot carried by one end of said presser-bar, and a spring depressing the presser-bar and the presser-foot carried thereby; means for lifting the presser-bar in opposition to said spring, comprising a rod journaled adjacent and substantially parallel to the presser-bar, a first arm projecting laterally from said rod and engaging the presser-bar, a second arm secured to said rod and projecting laterally therefrom, and means connected with said second arm for turning the rod about its longitudinal axis to cause the first arm to lift the presser-bar.

2. In a sewing machine having a horizontally disposed presser-bar pivoted on a horizontal axis and having a laterally offset portion, a presser-foot carried by one end of said presser-bar, and a spring depressing the presser-bar and the presser-foot carried thereby; means for lifting the presser-bar in opposition to said spring, comprising a rod journaled adjacent and substantially parallel to the presser-bar, a first arm projecting laterally from the forward end of said rod and engaging the offset portion of the presser-bar, a second arm secured to the rearward end of said rod and projecting laterally therefrom, and treadle-actuated means connected with said second arm for turning said rod to cause said first arm to lift the presser-bar.

3. In a sewing machine having a horizontally disposed presser-bar pivoted on a horizontal axis and having a laterally projecting stud, a presser-foot carried by one end of said presser-bar, and a first spring depressing the presser-bar and the presser-foot carried thereby; means for lifting the presser-bar in opposition to said spring, comprising a rod journaled adjacent and substantially parallel to the presser-bar, a second spring acting on said rod and biasing it in one direction, a stop to limit the turning movement of the rod under the influence of said second spring, a first arm projecting laterally from the forward end of said rod and located beneath the stud on the presser-bar, a second arm secured to the rearward end of said rod and projecting laterally therefrom, and treadle-actuated means connected with said second arm for turning the rod in opposition to said second spring to cause said first arm to engage said stud and thereafter to lift the presser-bar in opposition to said first spring.

4. In a sewing machine having a frame, a horizontally disposed presser-bar pivoted to said frame on a horizontal axis, a presser-foot carried by one end of said presser-bar, and a first spring depressing said presser-bar and said presser-foot carried thereby; means for lifting the presser-bar in opposition to said spring, comprising a rod journaled in the frame adjacent and substantially parallel to the presser-bar, a torsion spring surrounding said rod and acting thereon to bias it in one direction, a first arm projecting laterally from the forward end of said rod and adapted upon turning of said rod to engage beneath a portion of the presser-bar, a second arm secured to the rearward end of said rod and projecting laterally therefrom, and treadle-actuated means connected with said second arm for turning said rod to cause said first arm to lift the presser-bar in opposition to said first spring.

5. The combination with a sewing machine having a frame, a horizontally disposed presser-bar having one end pivotally connected to said

frame by a universal joint whereby said presser-bar is adapted to be moved vertically about a horizontal axis and to be swung horizontally about a vertical axis, a presser-foot connected to the other end of said presser-bar, and spring-actuated means carried by said frame for depressing said presser-bar and normally holding it against horizontal movement; of a presser-bar lifter comprising a rod journaled in said frame adjacent and substantially parallel to the presser-bar, a first arm projecting laterally from the forward end of said rod and engaging the presser-bar, a second arm secured to the rearward end of said rod and projecting laterally therefrom, means connected with said second arm for turning said rod to cause said first arm to lift the presser-bar, and means to withdraw said spring-actuated means from the presser-bar to permit the bar to be shifted horizontally.

6. The combination with a sewing machine having a frame, a horizontally disposed presser-bar having one end pivotally connected to said frame by a universal joint whereby said presser-bar is adapted to be moved vertically about a horizontal axis and to be swung horizontally about a vertical axis, a presser-foot connected to the other end of said presser-bar, and a spring-pressed plunger carried by said frame and engaging said presser-bar for depressing the presser-bar and normally holding it against horizontal movement; of a presser-bar lifter comprising a spring-biased rod journaled in said frame adjacent and substantially parallel to the presser-bar, a first arm projecting laterally from the forward end of said rod and engaging the presser-bar, a second arm secured to the rearward end of said rod and projecting laterally therefrom, treadle-actuated means connected with said second arm for turning said rod in opposition to its biasing spring to cause said first arm to lift the presser-bar, and finger-actuated means to withdraw said spring-pressed plunger from the presser-bar to permit the bar to be shifted horizontally.

7. A sewing machine comprising a frame, a presser-bar pivoted thereto on substantially horizontal and vertical pivots, a presser-foot secured to the forward end of said presser-bar, a spring-pressed plunger mounted in said frame and having a portion bearing upon and straddling the presser-bar to depress the same and the presser-foot and to prevent horizontal movement thereof, and means to withdraw the plunger from the presser-bar thereby to release the presser-bar to permit it to be swung horizontally about its vertical pivot.

8. A sewing machine comprising a frame having a tubular portion, a presser-bar pivoted at one end to said frame on substantially horizontal and vertical axes and extending beneath said tubular

portion, a presser-foot secured to the free end of said presser-bar, a spring-pressed plunger mounted in the tubular portion of said frame and having a portion bearing upon and engaging the presser-bar to depress the same and the presser-foot and to prevent horizontal movement thereof, and a finger-lever pivotally mounted on said tubular portion and engaging said plunger to withdraw the plunger from the presser-bar, thereby to release the presser-bar to permit it to be swung horizontally about its vertical pivot.

9. A sewing machine comprising a frame having a cylindrical bore, a presser-bar pivoted to said frame on substantially horizontal and vertical axes and extending beneath said bore; a presser-foot secured to the forward end of said presser-bar, a spring-pressed plunger mounted in said bore and having a bifurcated head portion bearing upon and straddling the presser-bar to depress the same and the presser-foot and to prevent horizontal movement thereof, and a finger lever pivotally supported upon said frame and engaging a portion of said plunger to withdraw the plunger from the presser-bar thereby to release the presser-bar and permit it to be swung horizontally about its vertical pivot.

10. A sewing machine comprising a frame, a horizontally disposed presser-bar pivoted to said frame on horizontal and vertical pivots, a presser-foot carried by one end of said presser-bar, a spring-pressed plunger mounted in said frame and having a portion engaging the presser-bar to depress the same and the presser-foot and normally hold them against horizontal movement, treadle-actuated means for lifting the presser-bar in opposition to said spring-pressed plunger comprising a rod journaled adjacent and substantially parallel to the presser-bar, a first arm projecting laterally from the forward end of said rod and engaging the presser-bar, a second arm secured to the rearward end of said rod and projecting laterally therefrom, means connected with said second arm for turning said rod to cause said first arm to lift the presser-bar, and a finger-actuated lever pivotally mounted on said frame and engaging said spring-pressed plunger and adapted to withdraw the plunger from the presser-bar to permit the presser-bar to be swung horizontally about its vertical pivot.
